UNITED STATES PATENT OFFICE

ROSS ZUMWALT, OF WEST BADEN, INDIANA

ENGINE

Application filed June 22, 1928. Serial No. 287,506.

This invention relates to rotary steam engines, and contemplates a construction and arrangement of parts wherein the sliding abutment for the rotor and the valve actuated mechanism to control the inlet of steam to the rotor, are both actuated in a novel manner and from opposite ends of the shaft of the rotor, the invention residing in the construction, combination and arrangement 10 of parts as claimed.

In the drawings forming part of this application like numerals of reference indicate similar parts in the several views and wherein:

15 Figure 1 is a side elevation of the engine.
Figure 2 is an end elevation.
Figure 3 is a top plan view.

Figure 4 is a fragmentary sectional view showing the steam inlet pipe and valve 20 therefor.

Figure 5 is a view of the engine with one of the slide plates removed showing the rotor.

Figure 6 is a sectional view on line 6—6 of Figure 1.

25 Figure 7 is a sectional view on line 7—7 of Figure 5.

Figure 8 is a sectional view on line 8—8 of Figure 5.

Figure 9 is a view in elevation of one of 30 the disks having the cam-shaped groove therein.

The engine forming the subject matter of the present invention embodies spaced side plates 10 and 11, which are of relatively different thicknesses, and both supported by a suitable base 12. The plates 10 and 11 are susceptible of adjustment toward and away from each other by means of adjusting bolts 13 to maintain a proper fit between these 40 plates and the rotor 14. The rotor is mounted upon a shaft 15 journaled on the plates 10 and 11, and the means for operating the abutment for the rotor and also the means for controlling the operation of the fuel inlet valve 45 are controlled from the shaft 15 in a manner to be hereinafter described. The rotor is provided with spring pressed packing 16 which bears against the opposed plates 10 and 11, and as illustrated in Figure 4 the rotor communicates with the steam supply pipe 17.

This communication is controlled by a valve 18. The rotor is provided with the usual semicircular opening 19, while the plate 10 is provided with a transverse bore or passage 20 in which the sliding abutment 21 operates. The abutment is also provided with spring influenced packing as clearly illustrated in Figure 6.

55 Mounted on the opposed ends of the shaft 15 are disks 22 and 23 respectively, the former being used in connection with means for controlling the movements of the sliding abutment 21, while the latter mentioned disk is used in connection with the valve operating means to be hereinafter described. 60 The disk 22 is provided with a cam-shaped groove 24 as clearly illustrated in Figure 9, and operated in this groove is a pin 25 supported on one end of an arm 26, the other end of the arm being pivotally mounted on 65 the plate 10. Pivoted on the pin 25 is a link 27, one end of which is connected with a bell crank lever 28 fulcrumed as at 29, and this lever 28 is also connected with the link 30 which connects the lever 28 with the sliding 70 abutment 21. Consequently as the shaft 15 rotates, similar movement is imparted to the disk 22, and the pin 25 riding in the cam-shaped groove 24 operates the bell crank lever 28 to control the movements of the sliding abutment to its active and inactive positions as will be readily understood.

75 The disk 23 is provided with a cam-shaped groove 31 similar to the groove 24 of the disk 22, and operating in the groove 31 is a pin 32 which is supported by one end of a link 33, the other end of which is pivoted on the plate 11. A link 34 is pivoted on the pin 32 and has its other end eccentrically connected with a wheel 35 carried by a shaft 36 journaled in 80 suitable bearings on the plates 10 and 11. Projecting from this shaft is an extension 37 which is connected with the adjacent U-shaped extremity 38 of a coupling member 39, the opposite end of which is also U-shaped 85 and connected with the extension 40 projecting from the valve 18. By reason of this construction and arrangement of parts it is manifest that as the disk 32 is rotated with the shaft 15 movement will be imparted to the 90 95 100

shaft 36 which is associated with the valve stem 18 by the universal joint just described, and the valve 18 is therefore opened and closed at the proper time to admit steam to the rotor 14. This steam is exhausted through the exhaust port 41 during the rotation of the rotor as will be readily understood.

While it is believed that from the foregoing description the nature and advantages of the invention will be readily understood, I desire to have it known that I do not limit myself to what is herein shown and described and that such changes may be resorted to when desired as fall within the scope of what is claimed.

What is claimed is:

1. An engine of the character described comprising spaced plates, a shaft journaled thereon, a rotor carried by the shaft and operating between said plates, means for adjusting said plates toward and away from each other and said rotor, a sliding abutment for said rotor, means for operating said abutment, an inlet pipe communicating with the rotor, a valve controlling said communication, a disk carried by said shaft, a second shaft rotatably mounted on the upper edges of said plates and parallel with the rotor shaft, an extension rising from the second mentioned shaft, an extension projecting from the stem of the valve, a coupling member having U-shaped extremities arranged in right angular relation to each other and pivotally connected with said extensions, and means operated from said disk to rotate the second mentioned shaft incident to the rotation of said rotor.

2. An engine of the character described comprising spaced plates, a shaft journaled thereon, a rotor carried by the shaft and operating between said plates, a sliding abutment for said rotor, means for operating said abutment, an inlet pipe communicating with the rotor, a valve controlling said communication, a disk carried by said shaft and having a cam shaped groove, a second shaft rotatably mounted on the upper edges of said plates and parallel with the rotor shaft, an extension rising from the second named shaft, an extension projecting from the stem of the valve, a coupling member having U-shaped extremities arranged in right angular relation to each other and pivotally connected with said extensions, a link pivoted on one of said plates, a pin projecting from one end of the link and operating in the groove of said disk, a wheel carried by one end of the second named shaft, and a link pivoted on said pin and eccentrically connected with said wheel, whereby the said shaft is rotated incident to the operation of said rotor.

In testimony whereof I affix my signature.
ROSS ZUMWALT.
